Primary Examiner — Derrick Holland*Assistant Examiner* — Lauren Calve(74) *Attorney, Agent, or Firm* — Kimberly-Clark Worldwide, Inc.(57) **CLAIM**

We claim the ornamental design for a wiping substrate dispenser, as shown and described.

DESCRIPTION

FIG. 1 is a perspective view of a wiping substrate dispenser showing our new design;

FIG. 2 is a side elevation view thereof;

FIG. 3 is an opposite side elevation view thereof;

FIG. 4 is a front elevation view thereof;

FIG. 5 is a back elevation view thereof; and,

FIG. 6 is a top plan view thereof.
